UNITED STATES PATENT OFFICE.

ARTHUR H. LIGHT, OF OAKLAND, CALIFORNIA.

HEATER.

Application filed October 9, 1922. Serial No. 593,481.

To all whom it may concern:

Be it known that I, ARTHUR H. LIGHT, a citizen of the United States, and a resident of the city of Oakland, county of Alameda, 5 and State of California, have invented new and useful Improvements in Heaters, of which the following is a specification.

My invention is particularly applicable to the heating of crude oil and the like to secure a proper combustion in oil furnaces. 10 This heating reduces the oil viscosity and establishes a fluid state, to enable it to be readily fired under the boilers.

The principal object of my invention is to 15 secure the transfer of heat from one fluid to another in the most efficient and economical way, and in apparatus smaller than that heretofore employed for an equivalent heating capacity.

20 A further object is the arrangement of the parts whereby the complete apparatus may be placed in a relatively confined space making it particularly applicable to the heating of fuel oil on vessels, or in other confined locations.

One of the objects of my heater is to provide apparatus which may be readily cleaned by the easy separation of interlocking parts whereby free oil-contacting surfaces are 30 readily exposed and space provided for the manipulation of cleaning tools.

Another object is the provision of heating units adjacent each other and forming with each other a tortuous passage of large exposed area through which the oil in its flow is caused to take on a turbulent movement or internal circulation, thus causing every particle thereof to come in close contact with the heated surface.

40 Other objects will appear from the drawings and specifications which follow.

Referring to the drawings:

Figure 1 shows one form of my heater especially adapted to the preheating of fuel oil with the two sections opened out preparatory to cleaning, shown in the lower portion of the figure, and in the upper portion of figure the two sections are shown bolted together.

50 Fig. 2 is a plan view of the heater of Fig. 1 with the two sections opened out, and showing portions of the heating units exposed.

Fig. 3 is a side view of Fig. 1 with the lower portion of the heater casing shown in

cross-section, and the heater units shown in full.

Fig. 4 is an assembly of two heaters connected together in operative position and adapted to parallel heating. 60

Fig. 5 is a section on the line V—V of Fig. 7.

Fig. 6 is a section of one of the heating units on the line VI—VI of Fig. 7.

Fig. 7 is a plan view of one of the heating units in one section of the heater and showing thereunder an adjacent heating unit mounted with the other section of the heater, the two units being shown in their relative position when the oil is caused to flow 70 therethrough.

Fig. 8 shows the arrangement of feed pipes and ports for steam or other heating fluid, and the corresponding drain ports from the heating units, and discharge connections therefrom, and the manner in which the heating units are supported against end distortion. 75

Fig. 9 is a diagrammatic showing of the manner in which my heater may be employed 80 for pre-heating the fuel oil for use under boilers. Fig. 10 shows a variation in my heater employing a cylindrical shell.

Throughout the figures similar numerals refer to identical parts. 85

My heater is preferably composed of two sections indicated respectively by the numerals 1, 2, which may be movably mounted as indicated by the davit 4 or hinge 3, and suitably supported as from a ship bulkhead 5. 90

When these two sections are bolted together as at 6, they form a closed chamber to which there is an inlet port 7 under the control of valve 8, and an outlet connection 95 9 under the control of valve 10.

Within this compartment 1 is a steam inlet 11 which is fed from the steam main 12 and which main also feeds a steam inlet 13 to the section 2. The steam pipes 11 and 13 100 pass through a glands as 14 and into a steam distributing pipe 15, the latter preferably enclosed within a discharge channel 16, within which channel the discharge from the heat units is collected and passes out 105 through the discharge pipe 17.

A similar steam distributing pipe, discharge channel, discharge pipe, and heating units are provided in the section 2 fed from the steam pipe 13, and when the two sec- 110

tions are bolted together as shown in the upper half of Fig. 3 and the unions 27 coupled together, the heating units from the pipes 11 and 13 respectively will occupy the 5 position indicated in Fig. 5, at which time contact takes place between the adjacent heating units at 40, 41, 42, 43.

It will be understood that other forms of 10 corrugations or shapes of plates may be employed than those shown and which will result in the adjacent units contacting at different points. For example in Fig. 7 it will be seen that the crossing of the corrugations on superimposed plates will result in 15 contacting therebetween at the points 31, 32, 33, 34, as well as at the center 42. In this way the plates mutually support each other against internal pressure and the outer exposed heating units are supported in a similar manner by the adjusting screws 35, 36, 20 at the top and bottom respectively of the casing (see Fig. 8).

By referring to Fig. 2 showing the two 25 sections opened outwardly as for cleaning, and following the disconnecting of the unions 27, it will be seen that there is a pocket or open portion as at 40, 41 and these openings form a clearance space around the steam pipes 11 and 12 and their 30 discharge channels. Through these clearance spaces the oil is enabled to travel from the bottom of the compartment as it flows from the pipe 7 and in an upward direction, and following the path of the arrows 35 (see Fig. 3), passing between the external surfaces of adjacent heating units, first in one direction, then through the clearance passage 40; or 41, and thence in an opposite direction through the opposite clearance 40 space, then again reversing its direction, and so on gradually traveling in a tortuous path from the bottom towards the top, and finally out of the heater in a thoroughly heated condition through the pipe 9.

45 It is to be noted that during its passage through the path formed between adjacent plates it encounters ribs on one plate running in a direction counter to the ribs on an adjacent plate, and the oil is thus caused 50 to circulate at every point of variation in the cross-section of its flow. This causes an intimate contacting with the heated external surface of the heating units and thus the oil acquires its full heat transfer therefrom.

The corrugations of the plates cause a 55 turbulence or circulation within the moving oil and promote a more rapid transfer of heat by the intimate contact between the heated surface and every particle of flowing oil.

It is well known that in the heating of hydrocarbon oils as where they are pre-heated for firing purposes, the heaters here- 60 tofore employed have caused the oil to de-

posit carbon or other heavy inert material on the surface of the heater, thereby greatly reducing the efficiency and making necessary frequent cleaning of the oil passages and heating surfaces against which the oil 70 contacts, or the entire rejection of a heating coil.

By arranging the ribs or corrugations in accordance with my invention the unit surfaces may be readily cleaned. This is accomplished by opening out the heater sections as shown in the lower part of Fig. 1 and in Fig. 2 when the unit surfaces are separated and a scraping tool may be readily passed through the valleys of the corruga- 75 tions and over the unit surfaces.

Referring particularly to Fig. 9, a steam boiler is indicated at 50 which is fired from the fuel burner 51 which latter in turn is supplied with fuel from the tank 52 and forced therefrom by the pump 53, through either one or both of the heaters 54 or 55, depending upon the manipulation of the inlet and outlet valves for the steam and the fuel. From one or both of these heaters the 90 hot oil is transmitted through the pipes 9 to the burner 51 where it is atomized. The boiler 58 also supplies steam through the pipe 59 and thence as a heating fluid through 95 my heaters 54, 55, where more or less condensation occurs which is trapped at 60 and thence discharged into a hot well from which further boiler supply may be taken or may be otherwise used as desired.

The heater here shown and described is 100 particularly adapted to the preheating of fuel oil by steam; however, to those skilled in the art other uses will appear, and I desire to be understood as claiming my invention when applied to other uses in the interchange of heat and it may be employed for the cooling or heating of any fluids, whether gases or liquids by circulating a fluid at one temperature through one of the passage ways in contact with the walls of the units 105 through which the other fluid may be passed.

The operation is as follows:

Assuming that the heater is properly cleaned and assembled by bolting together the two half sections of Fig. 1 whereby the heating units will occupy the relative positions shown in Fig. 3; the heater is filled with fuel oil through the pipe 7 which flows between the plates and over their corrugations and about the clearance spaces 40, 41, 110 of the steam pipes previously described, under the action of the pump 53 or other suitable pressure. Steam is now turned through the pipe 12 from which it passes through the two steam columns 11, 13, and 115 thence through the openings 18, 19, 20, into each of the heating units attached to the steam pipe of each of the heater sections, thus highly heating each heater unit. The condensed or expanded steam returns 120 to the boiler 58. The oil passes through the pipes 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 670, 671, 672, 673, 674, 675, 676, 677, 678, 679, 680, 681, 682, 683, 684, 685, 686, 687, 688, 689, 690, 691, 692, 693, 694, 695, 696, 697, 698, 699, 700, 701, 702, 703, 704, 705, 706, 707, 708, 709, 710, 711, 712, 713, 714, 715, 716, 717, 718, 719, 720, 721, 722, 723, 724, 725, 726, 727, 728, 729, 730, 731, 732, 733, 734, 735, 736, 737, 738, 739, 740, 741, 742, 743, 744, 745, 746, 747, 748, 749, 750, 751, 752, 753, 754, 755, 756, 757, 758, 759, 750, 751, 752, 753, 754, 755, 756, 757, 758, 759, 760, 761, 762, 763, 764, 765, 766, 767, 768, 769, 770, 771, 772, 773, 774, 775, 776, 777, 778, 779, 770, 771, 772, 773, 774, 775, 776, 777, 778, 779, 780, 781, 782, 783, 784, 785, 786, 787, 788, 789, 780, 781, 782, 783, 784, 785, 786, 787, 788, 789, 790, 791, 792, 793, 794, 795, 796, 797, 798, 799, 790, 791, 792, 793, 794, 795, 796, 797, 798, 799, 800, 801, 802, 803, 804, 805, 806, 807, 808, 809, 800, 801, 802, 803, 804, 805, 806, 807, 808, 809, 810, 811, 812, 813, 814, 815, 816, 817, 818, 819, 810, 811, 812, 813, 814, 815, 816, 817, 818, 819, 820, 821, 822, 823, 824, 825, 826, 827, 828, 829, 820, 821, 822, 823, 824, 825, 826, 827, 828, 829, 830, 831, 832, 833, 834, 835, 836, 837, 838, 839, 830, 831, 832, 833, 834, 835, 836, 837, 838, 839, 840, 841, 842, 843, 844, 845, 846, 847, 848, 849, 840, 841, 842, 843, 844, 845, 846, 847, 848, 849, 850, 851, 852, 853, 854, 855, 856, 857, 858, 859, 850, 851, 852, 853, 854, 855, 856, 857, 858, 859, 860, 861, 862, 863, 864, 865, 866, 867, 868, 869, 860, 861, 862, 863, 864, 865, 866, 867, 868, 869, 870, 871, 872, 873, 874, 875, 876, 877, 878, 879, 870, 871, 872, 873, 874, 875, 876, 877, 878, 879, 880, 881, 882, 883, 884, 885, 886, 887, 888, 889, 880, 881, 882, 883, 884, 885, 886, 887, 888, 889, 890, 891, 892, 893, 894, 895, 896, 897, 898, 899, 890, 891, 892, 893, 894, 895, 896, 897, 898, 899, 900, 901, 902, 903, 904, 905, 906, 907, 908, 909, 900, 901, 902, 903, 904, 905, 906, 907, 908, 909, 910, 911, 912, 913, 914, 915, 916, 917, 918, 919, 910, 911, 912, 913, 914, 915, 916, 917, 918, 919, 920, 921, 922, 923, 924, 925, 926, 927, 928, 929, 920, 921, 922, 923, 924, 925, 926, 927, 928, 929, 930, 931, 932, 933, 934, 935, 936, 937, 938, 939, 930, 931, 932, 933, 934, 935, 936, 937, 938, 939, 940, 941, 942, 943, 944, 945, 946, 947, 948, 949, 940, 941, 942, 943, 944, 945, 946, 947, 948, 949, 950, 951, 952, 953, 954, 955, 956, 957, 958, 959, 950, 951, 952, 953, 954, 955, 956, 957, 958, 959, 960, 961, 962, 963, 964, 965, 966, 967, 968, 969, 960, 961, 962, 963, 964, 965, 966, 967, 968, 969, 970, 971, 972, 973, 974, 975, 976, 977, 978, 979, 970, 971, 972, 973, 974, 975, 976, 977, 978, 979, 980, 981, 982, 983, 984, 985, 986, 987, 988, 989, 980, 981, 982, 983, 984, 985, 986, 987, 988, 989, 990, 991, 992, 993, 994, 995, 996, 997, 998, 999, 990, 991, 992, 993, 994, 995, 996, 997, 998, 999, 1000, 1001, 1002, 1003, 1004, 1005, 1006, 1007, 1008, 1009, 1000, 1001, 1002, 1003, 1004, 1005, 1006, 1007, 1008, 1009, 1010, 1011, 1012, 1013, 1014, 1015, 1016, 1017, 1018, 1019, 1010, 1011, 1012, 1013, 1014, 1015, 1016, 1017, 1018, 1019, 1020, 1021, 1022, 1023, 1024, 1025, 1026, 1027, 1028, 1029, 1020, 1021, 1022, 1023, 1024, 1025, 1026, 1027, 1028, 1029, 1030, 1031, 1032, 1033, 1034, 1035, 1036, 1037, 1038, 1039, 1030, 1031, 1032, 1033, 1034, 1035, 1036, 1037, 1038, 1039, 1040, 1041, 1042, 1043, 1044, 1045, 1046, 1047, 1048, 1049, 1040, 1041, 1042, 1043, 1044, 1045, 1046, 1047, 1048, 1049, 1050, 1051, 1052, 1053, 1054, 1055, 1056, 1057, 1058, 1059, 1050, 1051, 1052, 1053, 1054, 1055, 1056, 1057, 1058, 1059, 1060, 1061, 1062, 1063, 1064, 1065, 1066, 1067, 1068, 1069, 1060, 1061, 1062, 1063, 1064, 1065, 1066, 1067, 1068, 1069, 1070, 1071, 1072, 1073, 1074, 1075, 1076, 1077, 1078, 1079, 1070, 1071, 1072, 1073, 1074, 1075, 1076, 1077, 1078, 1079, 1080, 1081, 1082, 1083, 1084, 1085, 1086, 1087, 1088, 1089, 1080, 1081, 1082, 1083, 1084, 1085, 1086, 1087, 1088, 1089, 1090, 1091, 1092, 1093, 1094, 1095, 1096, 1097, 1098, 1099, 1090, 1091, 1092, 1093, 1094, 1095, 1096, 1097, 1098, 1099, 1100, 1101, 1102, 1103, 1104, 1105, 1106, 1107, 1108, 1109, 1100, 1101, 1102, 1103, 1104, 1105, 1106, 1107, 1108, 1109, 1110, 1111, 1112, 1113, 1114, 1115, 1116, 1117, 1118, 1119, 1110, 1111, 1112, 1113, 1114, 1115, 1116, 1117, 1118, 1119, 1120, 1121, 1122, 1123, 1124, 1125, 1126, 1127, 1128, 1129, 1120, 1121, 1122, 1123, 1124, 1125, 1126, 1127, 1128, 1129, 1130, 1131, 1132, 1133, 1134, 1135, 1136, 1137, 1138, 1139, 1130, 1131, 1132, 1133, 1134, 1135, 1136, 1137, 1138, 1139, 1140, 1141, 1142, 1143, 1144, 1145, 1146, 1147, 1148, 1149, 1140, 1141, 1142, 1143, 1144, 1145, 1146, 1147, 1148, 1149, 1150, 1151, 1152, 1153, 1154, 1155, 1156, 1157, 1158, 1159, 1150, 1151, 1152, 1153, 1154, 1155, 1156, 1157, 1158, 1159, 1160, 1161, 1162, 1163, 1164, 1165, 1166, 1167, 1168, 1169, 1160, 1161, 1162, 1163, 1164, 1165, 1166, 1167, 1168, 1169, 1170, 1171, 1172, 1173, 1174, 1175, 1176, 1177, 1178, 1179, 1170, 1171, 1172, 1173, 1174, 1175, 1176, 1177, 1178, 1179, 1180, 1181, 1182, 1183, 1184, 1185, 1186, 1187, 1188, 1189, 1180, 1181, 1182, 1183, 1184, 1185, 1186, 1187, 1188, 1189, 1190, 1191, 1192, 1193, 1194, 1195, 1196, 1197, 1198, 1199, 1190, 1191, 1192, 1193, 1194, 1195, 1196, 1197, 1198, 1199, 1200, 1201, 1202, 1203, 1204, 1205, 1206, 1207, 1208, 1209, 1200, 1201, 1202, 1203, 1204, 1205, 1206, 1207, 1208, 1209, 1210, 1211, 1212, 1213, 1214, 1215, 1216, 1217, 1218, 1219, 1210, 1211, 1212, 1213, 1214, 1215, 1216, 1217, 1218, 1219, 1220, 1221, 1222, 1223, 1224, 1225, 1226, 1227, 1228, 1229, 1220, 1221, 1222, 1223, 1224, 1225, 1226, 1227, 1228, 1229, 1230, 1231, 1232, 1233, 1234, 1235, 1236, 1237, 1238, 1239, 1230, 1231, 1232, 1233, 1234, 1235, 1236, 1237, 1238, 1239, 1240, 1241, 1242, 1243, 1244, 1245, 1246, 1247, 1248, 1249, 1240, 1241, 1242, 1243, 1244, 1245, 1246, 1247, 1248, 1249, 1250, 1251, 1252, 1253, 1254, 1255, 1256, 1257, 1258, 1259, 1250, 1251, 1252, 1253, 1254, 1255, 1256, 1257, 1258, 1259, 1260, 1261, 1262, 1263, 1264, 1265, 1266, 1267, 1268, 1269, 1260, 1261, 1262, 1263, 1264, 1265, 1266, 1267, 1268, 1269, 1270, 1271, 1272, 1273, 1274, 1275, 1276, 1277, 1278, 1279, 1270, 1271, 1272, 1273, 1274, 1275, 1276, 1277, 1278, 1279, 1280, 1281, 1282, 1283, 1284, 1285, 1286, 1287, 1288, 1289, 1280, 1281, 1282, 1283, 1284, 1285, 1286, 1287, 1288, 1289, 1290, 1291, 1292, 1293, 1294, 1295, 1296, 1297, 1298, 1299, 1290, 1291, 1292, 1293, 1294, 1295, 1296, 1297, 1298, 1299, 1300, 1301, 1302, 130

through the outlets as 24, 25, 26, into the discharge column 16 and thence as condensate or expended steam through the pipes 17, 17, to the trap 60. The steam will therefore, by heating the surface of the heating units, effect a high heating of the oil flowing through the heater as previously described.

The oil outflow from the heaters is through the pipe 9 which of course should be suitably heat insulated, and will now be continuous through the strainer 61 to the burner 51 as long as required. After prolonged action of the hot metallic surfaces of the heat units against a hydrocarbon fuel oil a greater or less deposit will inevitably occur on said surfaces, and it will be necessary to clean them in order to maintain the heating and the flowing efficiency through the heater. This cleaning I accomplish by first shutting off the oil and steam and after the heater has cooled, disconnecting the unions 27, 27 and unbolting the two sections and swinging them apart as shown in Fig. 2. This results in separating the alternating heating units from each other and presenting their exposed surfaces freely for access by suitable tools. The deposited carbon may now be readily removed from the unit surfaces when the apparatus is ready for reassembling as shown in the upper part of Fig. 1 and for further use.

By mounting two of my heaters in parallel as shown in Figs. 4 and 9 either heater may be cut out and cleaned without interrupting the fuel supply through the other, so that continuous hot oil service may be maintained.

In forming my heating units I prefer to form them with tapering surfaces from the steam pipe towards the periphery so that as the interlocking units recede from each other there is provided an increasing clearance therebetween.

And when again closed together and just at the moment of reaching final position they interlock against each other, as at the points 40, 41, 42, 43, see Fig. 5, or at points 31, 32, 33, 34, or as may be otherwise required, thereby to support them against distortion from internal pressure, and on the ends against the set screws 35, 36, of Fig. 8.

I also prefer to leave an internal projecting boss or bumped-in portion as 46 whereby the two surfaces of any single unit as 44, 45, are prevented from collapsing due to external pressure, as that of the flowing oil. This is particularly advantageous at such times as the steam pressure may be reduced or cut off entirely, when the heating units are subject to the full pressure of the pump 53, see Fig. 9 and these bumped-in portions for supporting the walls may be located at as many points as desired to provide for safely carrying any external pressure.

Referring now specifically to Fig. 10,

wherein I have shown a variation in the heater construction employing similar heating units arranged in similar manner with a cylindrical shell, preferably of drawn or welded steel, indicated by the numeral 70 to 70 which are fitted cover plate 71 and bottom plate 72. Steam supply pipes as before are shown at 11 and 13 and discharge pipes 17 and 17. The heating units as before, are arranged about the steam supply pipe and the discharge pipe in the manner shown in Fig. 8; the requisite number of heating units are built up on the two pipes, which pipes are held in place by top and bottom glands 14, 14, within the steel shell. An inlet for the oil to be heated is shown at 7 and an outlet at 9 and the flow of the oil about the surface of the heating units is in a tortuous channel as shown by the arrows. When built in this form my heater may be readily cleaned by removing either of the heads 71 or 72 and withdrawing the assembled heating units from the shell 70 when they may be readily cleaned by inserting a tool between the surfaces.

I claim:

1. A heater comprising a chamber formed of co-operating section members each provided with a supply pipe for a heating fluid and a plurality of relatively flat hollow heating units supported from said pipe, the units in one of said members adapted to pass between the units of the other member and the outer surfaces of the units forming a tortuous passage for other fluid to be heated when the parts are assembled in operative relation, ports for the supply of heating fluid from the pipes to the units, discharge ports from each unit and a discharge passage for expended fluid, and inlet and outlet connections to said chamber for said other fluid.

2. A heater comprising a chamber formed of co-operating section members each provided with a supply pipe for a heating fluid and a plurality of relatively flat hollow heating units supported from said pipe, the units in one of said members adapted to pass between the units of the other member and the outer surfaces of the units forming a tortuous passage for other fluid to be heated when the parts are assembled in operative relation, ports for the supply of heating fluid from the pipes to the units, discharge ports from each unit and a discharge passage for expended fluid, and inlet and outlet connections to said chamber for said other fluid, portions of the surfaces of adjacent units contacting with each other to provide reinforcement against distortion.

3. A heater comprising a chamber formed of co-operating section members each provided with a supply pipe for a heating fluid and a plurality of relatively flat hollow heating units supported from said pipe, the

- units in one of said members adapted to pass between the units of the other member, and the outer surfaces of the units forming a tortuous passage for other fluid to be heated when the parts are assembled in operative relation, to receive the thrust of the adjacent surfaces of the top and bottom units.
4. In a heater, a plurality of hollow disc like heating units; the alternate units having clearance spaces on one side and the other units clearance spaces on the opposite side, said units supplied from two steam ports for the supply of heating fluid from the pipes to the units, discharge ports from each unit and a discharge passage spaced apart through a large part of the heating units for expended fluid, and inlet and outlet connections to said chamber for said other units contacting with each other to provide reinforcement against distortion and abut the heating units with inlet and outlet ports at the top and bottom of the chamber to receive the thrust of the adjacent surfaces of the top and bottom units.

ARTHUR H. LIGHT.
